UNITED STATES PATENT OFFICE

JOHN LESLIE RICE, OF DAYTON, OHIO

DISPLAY DEVICE

Application filed September 4, 1930. Serial No. 479,667.

This invention relates to display charts and to means for supporting said charts, when displayed, and for conveniently carrying the charts.

Salespeople who sell articles of unusual proportion or weight such as stoves, electric refrigerators, cash registers, etc., often lose sales because the prospective customer is unable to visualize the article in its actual size in his own home or place of business. Where-as if the prospect could see a full sized representation of the article under consideration he could better determine if it was of suitable size, etc. Also, with a full sized illustration of his products before his customer, the salesman can better explain the advantages and superiority of his product.

However it is very costly and impractical to actually transport and install such articles merely for purpose of demonstration.

It is therefore an object of my invention to provide a novel, portable display stand, which, when set up and adjusted, presents a full sized portrayal of an article.

Another object is to provide a novel display device adapted to fold into a compact carrying case which case, when the device is in use, forms a part of the device.

Still another object is to provide a novel portable display device with a plurality of spring operated rolls carrying a chart having a full sized illustration thereon of an article to be demonstrated, said charts being interchangeable on the rollers.

A further object of my invention is to provide a portable display device with a novel carrying case having chart carrying rolls mounted therein, said case being adapted to be mounted on a stand to form a support and enclosure for the rollers when displaying the charts.

With these and incidental objects in view, the invention consists of certain novel features of construction and combination of parts, the essential elements of which are set forth in the appended claims and a preferred form or embodiment of which is hereinafter described with reference to the drawings which accompany and form a part of this specification.

In said drawings:

Fig. 1 is a perspective view of my display device with the combination carrying case and chart roll support mounted on its tripod and having one of the charts partially displayed. 55

Fig. 2 is a detail view showing the manner of retaining the rolls in the case.

Fig. 3 is a sectional view showing the relation of the elements of the device when in 60 use.

Fig. 4 is a detail view showing the structure of the rolls and charts and the manner of interchanging the charts on the rolls.

Fig. 5 is a perspective view of the case with the lid open showing the rolls, the mounting socket and the compartment in which the folded stand or tripod is carried. 65

My display device includes a casing 10 which may be of any suitable material, preferably thin sheet metal for strength and compactness. A lid 11 is secured to one side of the casing by hinges 12 and a latch 13 is provided to latch the lid in closed position when the device is not in use. A handle 14, attached to one side of the case, provides a convenient medium for carrying the device. 70

The size of the case and the appurtenant devices is determined entirely by the size of the article it is desired to display and the number of chart rolls desired. It is to be understood that the length of the rolls and the number of rolls provided in the case may be varied to suit the demand or the use to which the device is to be adapted without departing from the spirit of the invention. For illustrative purposes the case is shown provided with two chart rolls 15. The rolls being identical are indicated by the same reference numeral. 85

The rolls 15 are of the window shade type except that I provide said rolls with the longitudinal groove 16 in the periphery thereof with a semi-closed aperture. The upper end of the chart 17 is provided with a beading 18 which may be slid into the groove 16, thus securing the chart to the roll. By using this arrangement the charts are readily interchangeable whereby a maximum number

ber of charts may be used with a minimum number of rolls.

It is not thought necessary to include in this specification a detailed description of 5 the construction of the spring device for the roll as it is of well known construction. The spring (not shown) is tensioned when the chart is unrolled and the usual latch (not shown) is provided to retain the chart in 10 its unrolled position. When manually released, by slightly advancing the roll, the spring rotates the roll to rewind the chart thereon.

The rolls 15 are removably supported at 15 one end of the case by a bracket 19 secured to the inside of one end wall of the case. The other end of the rolls being supported in a bracket 20, secured to the inside of the other end wall of the case. The axle (not 20 shown) on the spring motor end of each of the rolls is inserted into an aperture (not shown) in the bracket 19 and a trunnion 21 secured to the other end of each roll is then dropped into an open slot 22 in the bracket 20. A locking arm 23, pivoted on a stud projecting from the bracket 20, is then moved to the position in which it appears in Fig. 2, where it is held by a projection 24 thereon engaging a hole in the bracket 20, thus holding the rolls 15 in position in the case.

When it is desired to use the display device, the case is inverted with the lid open and a bracket or socket 26, (Figs. 3 and 5) secured to the inside rear wall of the case opposite the handle, is fitted over the upper end of a tripod stand 27 or any suitable support. I prefer, however, to use a folding tripod, because when not in use the tripod may be folded up and conveniently carried 40 in a compartment provided in the case for that purpose. This compartment is formed by a partition 28 (Figs. 2, 3 and 4) and the rear wall of the case.

When the case is mounted on its support stand or tripod 27, the lid 11 hangs downward and a bracket 29 (Figs. 3 and 5) secured to the inner side of the lid, and having a notch 30 therein embraces the tripod 27 to brace the case against sidesway, thus insuring that the chart in use at the time will hang perpendicular to the floor. In the illustration (Fig. 1) the chart is shown only partially unrolled. It is to be understood however that the chart in actual use may be drawn 55 downwardly to its full extent completely concealing the support or tripod. The inverted case besides forming a convenient support for the chart rolls also affords a means for completely concealing the rolls from view 60 when the device is in use.

The lower end of the chart is formed into a loop into which is inserted a small metal rod having its ends 32 projecting beyond the chart 17 (see Fig. 1). This rod is of sufficient 65 weight to prevent the chart 17 from curling,

and holds the lower end thereof at the point to which it is lowered.

When the chart is rewound on its roll the rod is drawn upwardly and the ends 32 coming into contact with the brackets 19 and 20 arrest the rolling movement, otherwise the roll would rotate until its spring (not shown) was exhausted.

While the form of mechanism herein shown and described is admirably adapted to fulfill the object primarily stated it is to be understood that it is not intended to confine the invention to the one form or embodiment herein disclosed, for it is susceptible of embodiment in various forms all coming within 80 the scope of the claims which follow.

What is claimed is:

1. A device for carrying and displaying charts including a case; means in the case to support a plurality of rolls, each roll having a chart wound thereon; means on the case to receive a support rod; and means on the case to cooperate with said rod to brace said case.

2. In a case for carrying and displaying charts including a lid; the combination of means secured to the inner end walls of the case to support a plurality of rolls, each roll having a chart wound thereon; means secured to the case to receive a support rod; and means on the lid cooperating with said rod to brace the case.

3. In a case for carrying and displaying charts; the combination of means secured to the inner end walls of the case to removably support a plurality of rolls, said rolls having charts wound thereon; means to retain the rolls in the support means; and means on the case to receive a support rod whereby the case is invertedly supported to form a concealing and supporting enclosure for the rolls.

4. In a case for carrying and displaying charts; the combination of means secured to the inner end wall of the case, but spaced apart therefrom, to removably support a plurality of rolls, said rolls having charts wound thereon; pivoted means to retain the rolls in the support case; and means in the case to receive a support rod to invertedly support the case to form a concealing and supporting enclosure for the rolls.

5. In a case for carrying and displaying charts including a lid; the combination of brackets secured to the inner end wall of the case, but spaced apart therefrom, to removably support a plurality of rolls, said rolls having charts wound thereon; means pivoted on one of the brackets to retain the rolls in the support means; means secured to the case to receive the support rod to invertedly support the case; and means on the lid to cooperate with the support rod, when the lid is open, to brace said case.

6. In a case for carrying and displaying

charts including a lid; the combination of brackets secured to the inner end walls of the case, but spaced apart therefrom; a plurality of rolls removably supported by the brackets, each roll having a chart wound thereon; a locking arm to retain all of the rolls in position; a socket secured to an inner wall of the case to receive a support rod to invertedly support the case; and a bracket on the lid to embrace the support rod to prevent rocking movement of the case.

7. In a case for carrying and displaying charts including a lid; the combination of brackets secured to the inner end walls of the case, said brackets being provided with suitable apertures to receive a plurality of rolls; a locking arm pivoted on one of the brackets to retain the rolls in position; a socket secured to the inner wall of the case to receive a support rod to invertedly support the case, whereby the case forms a concealing and supporting enclosure for the rolls when the charts are being displayed; and a bracket on the inner side of the lid to cooperate with the support rod to brace the case.

In testimony whereof I affix my signature.
JOHN LESLIE RICE.
